UNITED STATES PATENT OFFICE.

WALTER BALLOU, OF NORTH ATTLEBOROUGH, MASSACHUSETTS.

DESIGN FOR AN ORNAMENTAL CHAIN.

SPECIFICATION forming part of Design No. 13,714, dated March 13, 1883.

Application filed January 22, 1883. Term of patent 14 years.

To all whom it may concern:

Be it known that I, WALTER BALLOU, a citizen of the United States, residing at North Attleborough, in the county of Bristol and State of Massachusetts, have invented and produced a new and original Design for Ornamental Chains, of which the following is a full, clear, and exact description, reference being had to the accompanying drawings, forming part of this specification.

Figure 1 is a perspective view of my newly-designed ornamental chain. Fig. 2 is a view of a modification of the design.

Ornamental chains have heretofore been made of tubes secured together parallel to each other, and such tubes have been heretofore made with plain burnished surfaces, and also with ornamental surfaces; but such chains have always been made up of a number of these tubes of the same kind.

The leading feature of my design consists in placing plain burnished tubes between ornamented tubes, so that the chain consists of alternate plain and ornamental tubes, as is clearly

shown in the drawings, in which *a a* are plain burnished tubes, and *b b* ornamented tubes.

I do not wish to confine myself to any particular kind of ornamentation for the ornamented tubes, as the peculiar and novel effect is produced by the alternately plain burnished and the ornamented tubes.

It is obvious that these chains may be used for all purposes for which ornamental chains are used, among which is the use for bracelets.

Having thus described my invention, I claim as new and desire to secure by Letters Patent—

The design for ornamental chains, the same consisting of alternately plain burnished and ornamental tubes placed side by side, as described.

WALTER BALLOU.
